Inventor:

James M. Wood

United States Patent Office.

JAMES M. WOOD, OF LOWVILLE, NEW YORK.

Letters Patent No. 74,473, dated February 11, 1868.

IMPROVEMENT IN ROOFING-SHOES.

The Schedule referred to in these Letters Patent and making part of the same.

TO ALL WHOM IT MAY CONCERN:

Be it known that I, JAMES M. WOOD, of Lowville, in the county of Lewis, and State of New York, have invented a new Improved Mode of Preventing Accidents by Slipping or Falling Off from House-Roofs or Roofs of other Buildings, while engaged in shingling the same, thus rendering the walking or moving over roofs safe and secure to all persons wearing my improved shoe or boot for the purpose; and I do hereby declare that the following is a full and exact description thereof, reference being had to the accompanying drawing, and letters of reference marked thereon, making part of this specification.

The nature of my invention consists in providing the bottom surfaces of the soles and heels of boots or shoes with perforated plates of iron; by punching holes in same, so as to produce a rasp or grater-like surface on one face of said iron plates, and by attaching the smooth faces of said plates in contact with the soles and heels of the boots or shoes, so that a rough exterior surface of a peculiar character is thus given to those parts of the boots or shoes required for standing on. The peculiarity of said roughness results from the sharp, jagged, or burred rims given to the perforations by the action of the punching.

The attachment of the plates so formed is accomplished by any of the known methods resorted to for securing taps and heels to shoes or boots. In this instance, I place the brass or iron plate A B (see drawing) at the toe of the shoe, as shown by the drawing, and secure the same to the soles by the screws A B, in such manner as to cover a small strip of the sole-plate C D. This covering, in addition to the screw C, secures completely the sole-plate C D to the shoe or boot-sole. The plate E is simply fixed, by the screw E, to the shoe or boot-heel.

Shoes or boots with the attachments described are intended to be used while engaged in shingling the roofs of houses or buildings, so as to enable the workman to have firm foot-hold, and to stand or move over said roofs with comparative safety and security. The adhesion (so to speak) imparted by the wearer of such attachments is proportionate to the pressure imparted, or as the weight of the party using same; and it is claimed that all tendency to slip off or slide from even a very steep roof will, with moderate caution, be altogether obviated by the use of this invention.

It is further deemed to be an important and valuable invention when availed of in cases of fire, as, by the use of a shoe or boot so protected, assistance can be extended with increased confidence by the parties wearing the same, by proceeding directly to the roofs of such premises.

What I claim as my invention, and desire to secure by Letters Patent, is—

The combination of the perforated plates A D E, when made in separate pieces, and secured to the sole of the boot or shoe, in the manner and by the means herein described.

JAMES M. WOOD.
